Patented Feb. 22, 1966

203,841

MINIATURE RACING CAR BODY

John M. Power, Playa Del Rey, Calif., assignor to Classic Industries, Inc., a corporation of California

Filed Apr. 7, 1965, Ser. No. 84,644

Term of patent 7 years

(Cl. D34—15)

Fig. 1

Fig. 3

FIG. 1 is a perspective view of a miniature racing car body, showing my new design;

FIG. 2 is a side elevation view; and
FIG. 3 is a rear elevation view.

I claim:

The ornamental design for a miniature racing car body, as shown.
